UNITED STATES PATENT OFFICE.

MARTIN VAN BUREN SMITH, OF NEW YORK, N. Y.

FURNACE.

No. 883,057.

Specification of Letters Patent. Patented March 24, 1908.

Application filed November 30, 1906. Serial No. 345,584.

To all whom it may concern:

Be it known that I, MARTIN VAN BUREN SMITH, a citizen of the United States of America, and a resident of New York city, 5 county, and State, have invented certain new and useful Improvements in Furnaces, of which the following is a specification, reference being had to the accompanying drawings, forming a part thereof.

10 My invention relates to improvements in furnaces, and particularly to improvements in puddling furnaces.

The main object of my invention is to provide a furnace in which both the temperature 15 and the quality of the flame in the puddling chamber may be varied and determined at will, and wherein a comparatively low degree of heat may be generated in the chamber in which the fuel is burned, which chamber is 20 usually termed the furnace or combustion chamber.

To these ends I provide a furnace of such a type as will first generate gases at a low temperature with a minimum of air, second, 25 I provide for admission of sufficient air only to the fuel to support initial combustion in the furnace chamber, while at the same time supplying air in relatively large quantities over the top of the fuel, and the combustible 30 gases evolved therefrom, so that the gases and air will pass together, but in a substantially unmixed state, into the puddling chamber, and third, I so baffle the air and gas at the end of the puddling chamber as 35 to cause the same to mix and to be deflected directly upon the material therein which is being treated.

My invention also consists in many novel features and combinations of parts as will be 40 hereinafter more fully set forth, and, in order that my invention may be thoroughly understood, I will now proceed to describe a furnace embodying my invention, having reference to the accompanying drawings 45 illustrating same, and will then point out the novel features in claims.

In the drawings: Figure 1 is a view in central longitudinal vertical section through a furnace constituting an embodiment of the 50 invention. Fig. 2 is a view in horizontal section therethrough. Fig. 3 is a detail view in vertical transverse section thereof, the plane of section being taken substantially upon the line 3—3 of Fig. 2. Fig. 4 is a de-

tail view in vertical transverse section there- 55 of, the plane of section being taken substantially upon the line 4—4 of Fig. 2.

The furnace comprises generally a combustion chamber 5 and a puddling chamber 6, the two said chambers inclosed in a structure of the general type known as reverberatory furnace. The combustion chamber and puddling chamber are divided by means of the usual bridge wall 7, and an arched dome 60 8 forms a roof for both, which roof acts to deflect the gases in a manner well understood.

The hearth, or fire grate, in the furnace chamber, comprises a number of plates or bars 9 supported upon cross bars 10, and arranged so close to each other as to form a 70 practically continuous support. In other words, this support is arranged to prevent the passage of air therethrough, instead of to permit it, as is usually the case in the grate bars which are ordinarily employed. Adjacent 75 this hearth, and between the ends of the bars 9 constituting same and the side of the bridge walls 7, is a fuel feeding means, here shown as an under-feed stoker. This stoker comprises a feeding chamber 11, in which is 80 arranged a feed screw 12 and a wind box 13 to which air is admitted through a supply pipe 14.

The wind box communicates with the interior of the feed chamber 11 through side 85 twyers 15, which admit a certain quantity of air to the fuel, as it is fed in, for the purposes of promoting combustion. The wind box 13 is, however, provided with large openings 16 in the side thereof which is furthest 90 away from the bridge wall 7, such openings being controlled by doors 17. These openings communicate directly with the space beneath the hearth, so that air, entering the wind box of the stoker, will pass freely 95 through the said openings into the said space. The forward ends of the bars 9 are so arranged as to permit free passage of the air thus introduced past same, which air will then pass around to the top of the fuel, there 100 to still further promote combustion. When considerable air is thus introduced, however, the larger quantity will pass upward to the top of the furnace beneath the dome 8 thereof, about as shown by the arrows in Fig. 1 of 105 the drawings. This air will continue along beneath the said dome 8 until it reaches the end of the chamber 6. At the end of this

chamber there is a dead wall 18, which will tend to deflect the air back again and cause the same to mingle with the combustible gases in the puddling chamber. An opening 5 19 is arranged comparatively well down in the said end wall 18, which will carry away the spent gases, but this opening—it is of comparatively small capacity—is still further choked by being continued in the form of a 10 plurality of vertical downwardly projecting passages 20 (see Figs. 1 and 2), said passages finally leading to a flue 21, which, in turn, carries the said spent gases to a main flue 22 with which a number of furnaces may connect, and which finally terminates in the base 15 of the main stack or chimney.

It will be noted that, while the portion of the furnace above described, which includes the combustion and puddling chambers up 20 to the dead wall 18, is of the reverberatory type of furnace; the portion in continuation thereof including the passages being substantially of the type of the Siemens regenerative furnace. At this part of the furnace 25 the gases are prevented from passing away until they have given up almost all of their heat, and, in order to still further baffle the same, I have provided a damper 23 in the flue 21, which may be closed to a greater or less degree as may be desired. In order to 30 prevent the possibility of burning the damper, and also in order to provide sufficient oxygen to burn up any carbon which may have come over into the flue in the form of 35 soot, I have fitted the damper loosely in the dome of the flue 21, so that air may be freely admitted in the space 24 behind same.

In operating a puddling furnace, it is well understood that the quality of the metal 40 produced varies greatly in accordance with the treatment it has received, and greater variations are produced by differences in the temperature and quality of the flame employed than by anything else. At certain 45 times a high temperature with a highly oxidizing flame is required, while, at other times, a high temperature with a non-oxidizing flame is necessary. Again, at other times a lower temperature is wanted. In general 50 a high degree of heat and an excess of air for oxidization purposes is required when first melting the pig iron, scrap, etc., because, during this operation, the silicon etc. is required to be oxidized. After the charge 55 is thus melted the temperature should be reduced, and the amount of air admitted greatly diminished. At this time oxid of iron, often in the form of scale, and commonly called "fix" is mixed with the molten metal. 60 This oxid of iron will at this time give up its oxygen, which, uniting with the carbon and remaining silicon of the pig iron, hastens its purification. This action causes the ebullition which is commonly called "boiling." 65 After the material has thus come to a boil,

the temperature of the flame is required to be raised so as to keep the puddling chamber at a high degree of heat, but at such time a non-oxidizing flame is required, and not an oxidizing flame, as during the first part of the 70 operation. Finally, under the influence of this heat and of the stirring, raking, separating and spreading about of the whole mass in the furnace, the "rabble," which is what the mixture is called up to this point, is finally 75 "flourished" or "brought to nature." When the iron is sufficiently "in nature" it is collected together in lumps or loops, and, during this time, the temperature may be more moderate, until, finally, the lumps or loops 80 which are now substantially in the form of balls, may be drawn from the furnace.

It has been a matter of the greatest difficulty in the past to properly regulate the temperature and quality of the flame, because, while it was possible to increase or decrease the temperature of the flame by increasing or decreasing the amount of oxygen supplied, it was a matter of great difficulty, and, in fact, almost an impossibility, to 90 properly regulate the oxidizing or non-oxidizing quality of the flame when sufficient air was supplied thereto to give a high temperature. In the present form of furnace, however, if excess of air is supplied to the 95 furnace, the said air will be caused to take such a path (illustrated in the drawings by the arrows) as will make the air readily available, not only for increasing the temperature of the flame, but also for producing an oxidizing effect upon the material. In other words, an excess of air, instead of producing 100 an oxidizing flame and a tremendous heat in the furnace chamber, will rise and pass along the roof of the furnace in a substantially 105 separate strata, but along with the gas, until finally, mixture of the same will take place in the puddling chamber instead of in the combustion chamber; and the excess of air not so combined with the products of combustion 110 will be in the proper location to be immediately effective in oxidizing the material as required.

The quality of flame generated in the combustion chamber is one in which there is as 115 little air as will properly support combustion, and the bars 9, being arranged close together side by side, will prevent air from being drawn up through the burning fuel, as is usual,—the major quantity of the air being 120 thus free to be delivered for mixture with the products of combustion in the puddling chamber instead of in the chamber 5, or for combining with the material being treated. I consider this to be broadly new, as, so far 125 as I am at present informed, complete combustion usually takes place in the furnace chamber, a sufficient quantity of air being always admitted for such purpose. For this reason I do not wish to be confined to any 130

particular form or arrangement of furnace, or of means for admitting fuel or air thereto. In the specific form of under-feed stoker which I have illustrated, I have merely intended to show one means by which fuel may be conveniently fed into the chamber 5. At the same time the form of the stoker is such as to form a ready and convenient means for admitting air for use both in the 10 combustion chamber and in the puddling chamber.

Beneath the furnace chamber I have provided an ash pit 25 with a water seal 26 to prevent air from blowing out therethrough. 15 I have also provided a suitable opening 27 in front of the ends of the bars 9, said opening being normally closed by doors 28. This opening will give the attendants free access to the bars, to the fire, and to the interior of 20 the furnace chamber for any purpose which may be necessary, permitting also the ready removal lengthwise of the bars 9 when desired.

What I claim is:

25 1. In a puddling furnace, the combination with a combustion chamber and means for evolving gases at a low temperature therein, of a puddling chamber adapted to receive gases thus evolved from the combustion chamber, means for supplying highly heated air from the combustion chamber to the puddling chamber in a condition substantially unmixed with the gases from the combustion chamber, and means within the puddling chamber to cause the mixture of the gas and air therein.

2. In a furnace, the combination with a combustion chamber for containing fuel, of a work chamber in which heat is to be applied, 40 said combustion and work chambers separated by a bridge wall, means for supplying air to be heated to the combustion chamber, and for carrying the heated air and the products of combustion, one over the other, across 45 the bridge wall into the work chamber, and deflecting means at the end of the work chamber opposite the bridge wall, for deflecting the air back toward the work and the incoming gases.

50 3. In a furnace, the combination with a combustion chamber for containing fuel, of a work chamber in which heat is to be applied, said combustion and work chambers separated by a bridge wall, means for supplying air to be heated to the combustion chamber, and for carrying the heated air and the products of combustion, one over the other, across 55 the bridge wall into the work chamber, and deflecting means at the end of the work chamber opposite the bridge wall, for deflecting the air back toward the work and the incoming gases, said deflecting means comprising a dead wall at the upper portion of the furnace, and provided with a restricted 60 opening for waste gases, below same.

4. In a furnace, the combination with a chamber containing a hearth for receiving the fuel for combustion, and a work chamber in which heat is to be applied, in communication with said combustion chamber, of 70 means for admitting air beneath and around said hearth and fuel contained therein, whereby said air will be directed toward the upper portion of said furnace chamber and into the work chamber at the upper portion thereof 75 over the top of the products of combustion, and deflecting means at the end of the work chamber opposite the combustion chamber, for deflecting the air back toward the lower portion of the work chamber and toward the 80 incoming gases.

5. In a puddling furnace the combination with a chamber containing a hearth for receiving the fuel for combustion, and a puddling chamber arranged in communication 85 with said combustion chamber, of means for admitting air beneath and around said hearth and fuel contained therein, whereby said air will be directed towards the upper portion of said furnace chamber and into the puddling 90 chamber at the upper portion thereof.

6. In a puddling furnace, the combination with a chamber for containing fuel for combustion purposes, and a puddling chamber separated from said combustion chamber by 95 a bridge wall, of a hearth in said combustion chamber for supporting said fuel therein, said hearth being substantially closed to passage of air therethrough, and said combustion chamber being provided with a passage 100 around the front end of said hearth, and means for admitting air beneath said hearth, whereby said air will pass around the front end of said hearth and up into the upper portions of said combustion and puddling chambers. 105

7. In a puddling furnace, the combination with a combustion chamber, and a puddling chamber, said chambers separated from each other by a bridge wall, of means for admitting fuel to said combustion chamber at a point contiguous to said bridge wall, a closed hearth for supporting fuel located adjacent to said fuel feeding means, said chamber being provided with an air passage around the front end of said hearth, and means for admitting air beneath said hearth, whereby the said air will pass around through the said passage to a point in the combustion chamber above the fuel therein. 110

8. In a puddling furnace, the combination with a combustion chamber and a puddling chamber separated by a bridge wall; of a mechanical stoker arranged contiguous to said bridge wall, a hearth arranged adjacent 125 said stoker for supporting fuel delivered therefrom, and means for admitting air to said stoker and to beneath said hearth, said combustion chamber provided with a passage around the front of said hearth through 130

which the air delivered beneath said hearth will pass around to a point in said chamber above the fuel contained therein.

9. In a puddling furnace, the combination with a combustion chamber and a puddling chamber separated therefrom by a bridge wall, of an under-feed stoker arranged contiguous to said bridge wall, a closed hearth for supporting fuel arranged immediately adjacent said stoker, means for admitting air to said stoker and also to beneath the said hearth, said chamber arranged with a passage around the front end of said hearth through which the said air thus delivered beneath the hearth will pass around to a point above the fuel contained on said hearth.

10. In a puddling furnace, the combination with a combustion chamber and a puddling chamber separated from each other by a bridge wall, of a stoker arranged immediately contiguous to said bridge wall, said stoker comprising a feed chamber, fuel feeding means therein, a wind box, a closed hearth arranged immediately adjacent said stoker and upon the side thereof opposite to the bridge wall, said chamber provided with a passage around the front end of said hearth from the lower to the upper side thereof, and said wind box provided with an opening into the space beneath said hearth, and means for admitting air to the wind box for supplying the stoker, and also for discharge through the

opening in the side wall thereof to the space beneath said hearth, whereby said air will pass around through the passage at the front of said hearth to the combustion chamber at a point above the fuel therein.

11. In a puddling furnace, the combination with a combustion chamber and a puddling chamber separated from each other by a bridge wall, of an under-feed stoker comprising a feed chamber, a conveyer screw therein and a wind box, said stoker arranged immediately contiguous to said bridge wall, a hearth arranged immediately adjacent said stoker, said hearth composed of a plurality of bars suitably supported and arranged close together, so that air will be substantially prevented from passing therethrough, said combustion chamber being provided with a passage around the front of said hearth, and with a door opposite said passage through which access to the said hearth may be had from the exterior of the furnace, the wind box of said stoker being provided with an opening therefrom to the space beneath said hearth, and with twyers opening into the feed chamber and means for admitting air to the said wind box.

M. VAN BUREN SMITH.
